[57] CLAIM

The ornamental design for a combined storage compartment, auxiliary rear seat and audio unit for a jeep type vehicle, as shown and described.

DESCRIPTION

FIG. 1 is a perspective view of a combined storage compartment, auxiliary rear seat and audio unit for a jeep type vehicle;

FIG. 2 is a top plan view thereof;

FIG. 3 is a front elevational view thereof;

FIG. 4 is a rear elevational view thereof;

FIG. 5 is a side elevational view thereof the opposite side being a mirror image of the side shown.

In FIG. 1 the broken line showing of a portion of a jeep type vehicle is for illustrative purposes only. The design shown in FIG. 1 is on a reduced scale compared to that of FIGS. 2-5.
